AIR CONDITIONING DEVICE

Emile P. Brus, Kansas City, Mo., assignor, by
mesne assignments, to Air Conditioning Equipment
Inc., a corporation of Missouri

Application January 10, 1934, Serial No. 706,067

1 Claim. (Cl. 62—129)

My invention relates to an air conditioning device and more particularly to a novel cooling means in combination with an air conditioning device.

5 One object of my invention is to provide an efficient cooling means for use in an air conditioning device.

Another object of my invention is to provide a novel air conditioning device which may be 10 made in small sizes so that portable units may be constructed.

Other and further objects of my invention will appear from the following description.

In general, my invention contemplates the 15 cooling of a condenser or a heat exchanger, through which the refrigerant fluid flows by the evaporation of water or other suitable liquid so that the latent heat of vaporization may be utilized for cooling purposes. The evaporation 20 is aided in my invention by a reduction of pressure which not only assists in the evaporation but is used as a means for jetting the liquid to be evaporated into a fine spray.

In the accompanying drawings which form 25 part of the instant invention and are to be read in conjunction therewith, and in which like reference numerals are used to indicate like parts in the various views:

Figure 1 is a sectional elevation of an air 30 conditioning device embodying one mode of carrying out my invention.

Figure 2 is a sectional view taken on a line 2—2 of Figure 1.

Figure 3 is an enlarged detail view of the 35 water spray.

Figure 4 is a sectional elevation of an air conditioning device, embodying another mode of carrying out my invention.

Figure 5 is a sectional view taken on a line 40 5—5 of Figure 4.

More particularly referring now to the drawings, a suitable casing or cabinet 1 houses a refrigerating coil 2 in proximity to which a blower fan 3, driven by an electric motor 4 or other 45 suitable means, is positioned. The blower is adapted to blow the air to be conditioned over the refrigerating coil 2. The refrigerating coil 2 is provided with heat exchange fins 5 as is customary in the art. A pan 6 is positioned 50 underneath the refrigerating coil 2 to cool the moisture precipitated from the air due to its being chilled below the dew point. A suitable motor 7 is connected to drive a compressor 8 and a vacuum pump 9. The refrigerant fluid in 55 the form of the invention shown in Figure 1

is compressed in compressor 8 and passed through line 10, through a condenser coil or heat exchanger coil 11, which is provided with suitable fins 12. The refrigerant fluid is cooled in the condenser or heat exchange coil 11 in a 5 manner that will be hereinafter more fully described, and passes through line 14, through surge tank 15, through line 16, through expansion valve 17, where it is expanded through refrigerating coil 2 and returned to the compressor 8, 10 through the line 18. A tank 20 is supplied with water 21 through filling connection 22. The condenser 11 is housed in a suitable casing 23, which is provided at its upper end with a spray head 24 shown most clearly in Figure 3. Spray head 15 24 is connected by a pipe 25 to the water 21 in tank 20. Line 25 is controlled by valve 26. The lower portion of the casing 23 is connected to vacuum pump 9 by line 27. The discharge from vacuum pump 9 is through line 28 which 20 leads outside the air space being conditioned. When a vacuum is pulled on casing 23, the air pressure acting on the top of water 21 will force water through the fine spray holes 29 in spray head 24. The water in a fine spray, being jettied 25 into the chamber 23 in which the condenser is situated and into the space maintained under reduced pressure by vacuum pump 9, will be vaporized in the form shown in Figure 1; the temperature of the compressed refrigerant fluid in 30 line 10 will be such that the water will be completely vaporized so that all that issues from pipe 28 will be a fine spray. It will be seen that the effect of jetting finely divided water over the extended surfaces of the condenser 11 and 35 the positioning of the condenser in a space maintained under reduced pressure causes a very efficient and very compact cooling arrangement.

The operation of the form of the invention shown in Figure 1 and Figure 2 will be obvious 40 from the foregoing description. The motor 1 is started and valve 26 is maintained closed until a vacuum or partial vacuum is applied in chamber 23. The valve 26 is adjusted so that the water spray is that necessary for the desired 45 cooling effect. The motor 4 blows air over the refrigerating coil. The refrigerant fluid is compressed and cooled in condenser 11 and expanded in refrigerating coil 2. Moisture precipitated from the air being conditioned collects in pan 6 50 from which it is drained through line 30, whence it passes into a body of water 21 within tank 20.

In the form of the invention shown in Figures 4 and 5, an expansion refrigerating apparatus is omitted and the entire cooling effect obtained by 55

the evaporation of the refrigerant liquid, which may be water or any other suitable liquid. If desired, a liquid more volatile than water may be used to increase the cooling effect. In practice, 5 however, the device may be made of sufficient size so that water may be used. The motor 7 is connected to drive a circulating pump 31 and vacuum pump 9. A tank 32, containing the refrigerant liquid 33 communicates with circulating pump 31, 10 through line 34. The refrigerant liquid is introduced through tank 32, through pipe 35, which is provided with a sealing means 36 so that the tank 32 may be sealed after liquid has been introduced thereinto. The pump 31 circulates liquid from 15 tank 32 through line 37, through cooling coil 38, which is provided with a drip pan 6, as before. A blower 3, driven by a motor 4 for passing air to be conditioned over the refrigerating coil 38 is noted. The refrigerating coil 38 is likewise provided with heat exchange fins 5. The refrigerant fluid, after passing through the refrigerating coil 38, passes through line 39, through heat exchanger 40, similar to condenser 11. The casing 23 is constructed as before and provided with a 20 spray head 24 having a line 25 communicating with a tank 20, provided with water 21. Line 25 is fitted with a control valve 26. The interior of casing 23 communicates with vacuum pump 9 through line 27. The discharge from the vacuum 25 pump 9 is through line 28 which terminates in an ejector 41. One leg 42 of the ejector 41 communicates with the interior of the tank 32. The refrigerant fluid, after being cooled in heat exchanger 40, passes through line 43 into spray head 35 44, whence it is sprayed as shown in Figure 4. The ejector will reduce the pressure existing within tank 32, the vapors passing from ejector 41, through line 45 to a point outside the space being conditioned.

40 In operation, the motor in the form of the invention shown in Figures 4 and 5 drives the circulating pump 31 and the vacuum pump 9. The vacuum pump 9 pulls a vacuum in the interior of the casing 23 so that the water from tank 21 45 is pulled and the enlarged space maintained at reduced pressure. The water is thus vaporized, the latent heat of vaporization being taken from the refrigerant fluid circulating through heat exchanger 40. The refrigerant fluid being sprayed 50 through the fine holes in pipe 44 also passes through an area maintained at reduced pressure so that there is a partial evaporation of the refrigerant fluid. The vapors of the refrigerant fluid and the vapors of the water from the interior of casing 23 pass outside of air space being conditioned, through pipe 45.

It will be seen that a double cooling effect is achieved. We have an evaporation of water and

an evaporation of the refrigerant fluid, the effect of both evaporation being to reduce the temperature of the refrigerant fluid which passes through the refrigerating coil 38.

It will be observed that I have accomplished the objects of my invention. I have provided a cooling means for an air conditioning device which is efficient and compact. The spraying of finely divided water into the zone of reduced pressure substantially necessitates the vaporization of 10 same. Thus I am enabled to furnish the latent heat of vaporization, water being vaporized from the refrigerant fluid, then cooled. In the form of the invention shown in Figures 4 and 5, I obtain an added cooling effect by evaporation of a portion of the fluid, thus enabling the dispensation of the compression expansion, refrigerating cycle. This enables me to eliminate valves and to avoid the necessity of using a compressor. This has the added advantage of giving a quiet device, free 20 from noise and, at the same time, to reduce the expense of the installation in that a small pump and an ejector are substituted for a compressor and achieve substantially the same result in a cheaper, quieter, and more expeditious manner. 25 This is of great importance further when a portable device is made, especially those devices designed for conditioning living spaces in the home and in the office where noise is extremely objectionable and space is at a premium.

It will be understood that certain features and sub-combinations are of utility and may be employed without reference to other features and sub-combinations. This is contemplated by and is within the scope of my claim. It is further 35 obvious that various changes may be made in details within the scope of my claim without departing from the spirit of my invention. It is, therefore, to be understood that my invention is not to be limited to the specific details shown and 40 described.

Having thus described my invention, what I claim is:

An air conditioning device including in combination, a housing, heat exchange means positioned within said housing, means for maintaining the housing under sub-atmospheric pressure, means for supplying liquid to said housing, a tank, a refrigerating coil, means for circulating a refrigerating medium from said tank, through said 45 refrigerating coil and back to said tank through said heat exchange means, a spray for spraying the circulating refrigerating medium back into said tank, means for maintaining said tank under sub-atmospheric pressure, means for passing air 50 to be conditioned over said refrigerating coil.

EMILE P. BRUS.
